US0D1021785S

(12) **United States Design Patent** (10) **Patent No.:** **US D1,021,785 S**
(45) **Date of Patent:** **** Apr. 9, 2024**

(54) **PORTABLE CHARGER**

(71) Applicants: **KUNSHAN AMPHENOL ZHENGRI ELECTRONICS CO., LTD.**, Kunshan (CN); **AMPHENOL LTW TECHNOLOGY CO., LTD.**, New Taipei (TW)

(72) Inventor: **Julien Jaya Philippe Kuoch**, New Taipei (TW)

(73) Assignees: **KUNSHAN AMPHENOL ZHENGRI ELECTRONICS CO., LTD.**, Kunshan (CN); **AMPHENOL LTW TECHNOLOGY CO., LTD.**, New Taipei (TW)

(**) Term: **15 Years**

(21) Appl. No.: **29/843,284**

(22) Filed: **Jun. 20, 2022**

(51) LOC (14) Cl. **13-02**

(52) U.S. Cl.

USPC **D13/108**
